UNITED STATES PATENT OFFICE.

GEORGE ROTTMAN, OF NEW YORK, N. Y.

BAG.

Application filed September 5, 1922. Serial No. 586,102.

To all whom it may concern:

Be it known that I, GEORGE ROTTMAN, a citizen of the United States, residing in New York, in the county of New York and 5 State of New York, have invented certain new and useful Improvements in Bags, of which the following is a specification.

My invention relates to an improved bag; particularly a moth-proof and dust-proof 10 bag in which clothes and garments can be sealed during the seasons when they are not needed for use.

An object of the invention is to provide a moth-proof and dust-proof bag which is 15 of simple design, strong construction and low manufacturing cost; which is provided inside with means for suspending clothes or garments, and outside with means preferably in the form of a hook for enabling the bag 20 to be hung up in a closet or other place of storage, the inside suspending means being of such a character that all risk of its tearing or damaging the bag is obviated, even when the bag is stored or packed when not 25 in service; and which is provided with fastening devices that will keep the bag securely closed and render it unlikely of accidentally coming open if carelessly handled.

Other objects and advantages of this invention will appear from the following description, taken with the accompanying drawings, which present several forms in which my invention can be embodied; and the novel features are defined in the appended 30 claims. The disclosure, however, is explanatory only and I reserve the right to make changes, not illustrated herein, with regard to the shape, size and arrangement of the parts, without departing from the scope and 35 spirit of the invention, as the same is indicated by the broad and general meanings of the terms in which the claims are expressed.

On the drawings:

Figure 1 is a front view of a bag according to my invention with the parts in position to give access to the inside of the bag;

Figure 2 is a rear view of the same bag with the parts in the same position;

Figure 3 is a front view of the same bag 50 closed;

Figure 4 is a perspective view of another form of bag with the entrance closed;

Figure 5 is a front view of the same bag, partly in section, as it appears when 55 lapsed or flattened;

Figure 6 is a sectional view taken longi-

tudinally through the closed side of the bag, with the parts in the position they assume when the bag is about to be distended;

Figure 7 is a view of the bag seen from 60 the side which is closed, when the bag is partly expanded;

Figure 8 is a section on the line 8—8, of Figure 4;

Figure 9 is a view similar to Figure 8 65 with the parts in the position they assume when moving to close the bag;

Figure 10 is a section on line 10—10, of Figure 1;

Figure 11 is a section on line 11—11, of 70 Figure 7;

Figure 12 is a section on line 12—12, of Figure 1;

Figure 13 is a section on line 13—13, of 75 Figure 1;

Figure 14 is a section on line 14—14, of Figure 6;

Figure 15 is a front view of a plate to be secured to the inside of the bag to suspend a garment therein;

Figure 16 is a top view of Figure 15, partly in section on the line 16—16 of Figure 15;

Figure 17 is a sectional view taken through one form of fastener shown in Figure 1;

Figure 18 is a similar sectional view of another clip or fastener used on the bag shown in Figures 1, 2 and 3; and

Figure 19 is a view of a disk or washer which is engaged by a rivet of the clip or 90 fastener shown in Figure 18 and helps to secure said clip in place.

The same numerals identify the same parts throughout.

The bag shown in Figures 1, 2 and 3 comprises a front 1 and back 2. It is closed at the bottom and the side at the right of Figure 1, but open on the opposite side and at the top. This bag can be made by taking a piece of strong paper or other suitable 95 material, and folding it in the middle to form two approximately equal portions, so as to make the front and back; and the place where the crease is made will therefore be the side that is to be permanently 100 shut. One edge of the front 1, for example, can be provided with a flap 3, to be folded over and pasted to the rear 2, so as to close the bag at the bottom and an outside hook 4 is attached to the back to enable the bag 105 to be hung up. Along the side opposite the closed side, both the front 1 and back 2 are 110

provided with parallel creases 5, marking off foldable portions 6 and 7. At the top of the bag are similar creases 8 marking off foldable portions 9 and 10. When the bag 5 is opened a garment can be inserted into it, simply by pulling the front 1 and back 2 apart along the open side and open top and suspending the garment from a hook on the interior of the bag. To close the bag one 10 then lays the sections 6 and 7 of the front against the corresponding sections 6 and 7 of the back and turns the two sections 7 over upon the section 6 of the front about the crease or score line 5 which separates 15 the sections 6 and 7 from one another. One next rotates the folded sections 6 and 7 about the other score line 5 so as to lay the folded sections 6 and 7 flat against the front of the bag with the section 6 of the back 2 20 uppermost. To seal the bag at the top, the sections 10 of the front and back are first turned about the upper crease 8 so as to cause the section 10 of the front to lie upon the section 9 of the front and the section 10 25 of the back to be presented forward. The sections 9 and 10 of the front and back are then folded together about the lower score line or crease 8 over upon the front 1 so as to bring the section 9 of the back forward 30 and make the ends of the folded sections 9 and 10 overlie sections 6 and 7, as shown in Figure 3.

The sections 6 and 7 along the side edges of front 1 and back 2 extend up and only 35 as far as the lower score line 8; and the sections 9 and 10 run from the closed side only as far as the beginning of the section 6. Hence, the upper left corner of the front 1 and the back 2, remote from the closed 40 side of the bag, presents a notched or cut-out effect and the ends of the sections 6, 7, 9 and 10 thereat may be reinforced by securing strips of suitable material 11 inside the bag. The lower ends of the sections 45 6 and 7 may be reinforced in the same way. As will be apparent from Figures 1, 2 and 3, the closed bottom of the bag extends only from the closed side over to the score line 5 which makes the beginning of the 50 section 6, and the lower ends of the sections 6 and 7 of the front of the bag are preferably not joined together.

When the top of the bag is closed, as 55 shown in Figure 3, it is kept closed by means of rotatable clips 12 shown fully in Figures 1, 2 and 17. These clips are pivotally secured by rivets 13 to plates or strips 14, fastened to the ends of the section 10 of the top 1. When the sections 60 9 and 10 of the top are folded over, the clips 12 are rotated outward, to clear the side edges of the bag; and when the sections 9 and 10 come into final position as shown in Figure 3, the clips 12 are turned 65 on their pivots 13 so as to extend from the

outer ends of the strips 14 across the side edges of the back 2 and engage the rear of the bag in such a way as to prevent the sections 9 and 10 from unfolding. The upper ends of the sections 6 and 7 70 are now held down by the sections 9 and 10, and along the front of the bag are rotatable clips 15 secured by rivets 16. When the side of the bag is closed by folding over the section 6 and 7, these clips 75 are turned on their pivots to extend across the folded sections 6 and 7 and hold them against the front face of the bag 1. The bag is thus securely closed along the top and one side, and to open it the clips 12 80 and 15 must be turned back to the position shown in Figures 1 and 2.

To enable the bag to be both flattened and distended to better advantage, the closed side of the bag is so folded as to provide a gusset. This result is accomplished by providing three creases instead of one at the closed side, so as to afford two internal longitudinal sections 17, which in effect make an internal pleat. When the bag is to be distended to receive a garment, it can therefore be expanded to greater extent and with less danger of tearing. The construction in question is illustrated particularly in Figures 10, 11 and 12, the former showing the closed side of the bag 90 as it appears when flattened, and Figure 11 how this closed side will appear when the bag is expanded in some degree. The sections 17 extend all the way from the top of the bag across the sections 8 and 9 down to the bottom, and the bottom edges of the sections 17 may be secured by pasting if desired, to the inside faces of the front 1 and back 2. I may also reinforce the 100 bag at the bottom by means of a strip 18, which can fold lengthwise and be secured by an adhesive or some other means to the inside faces of front 1 and back 2. This reinforcement 18 extends from the sections 6 over to the opposite side and is split in the middle of its end adjacent the sections 17 to extend across these sections, as indicated at the lower right hand corner 105 of Figure 1 and in Figure 12. Preferably 110 the outer edges of the sections 7 and 10 should be reinforced also.

The strips or plates 14 which mount the clips 12 are provided with tongues or barbs 19 and 20, the barbs 19 being made by pointing the ends of these strips and bending them over and the barbs 20 by cutting or stamping them from the body of the strip and bending them in the same direction as barbs 19, thereby leaving openings 21. The barbs are then driven through the ends of the front sections 10 and turned over tightly on the inside of the sections 10, thereby securing the strips 14 in place. 115 The hook 4 is pivotally attached to the 120 125 130

rear 2 by bending its lower end and passing it through a bearing 22 in a plate 23, the extremity of the shank of the hook 4 being turned upward as at 24 to prevent it from being pulled out of the bearing 22. This plate 23 is attached to the rear 2 of the bag by being provided with slots 25 which receive tongues 26. These tongues pass through the bag from the inside and through the slots 25 and are turned over or riveted against the plate 23, as indicated in Figure 2. The hook 4 can thus swing freely and suspend bag from a nail or other support.

15 The tongues or barbs 26, are carried by a plate 27; being cut or stamped therefrom; so that when the plate 27 is laid against the inside face of the back 2 and the points 26 forced through the bag and 20 into the slots 25 they can be bent against the outer face of the plate 23 and thus rivet the two plates 23 and 27 together, gripping the back 2 between them. The plate 27 has an integral vertical bearing 25 stamped from one face thereof to receive clothes or garments on a hook 29. The shank of this hook 29 passes through the bearing 28 and is bent over at its lower 28 end so that it cannot be pulled out of the bearing; but is free to swing therein. From the top of the bearing 28 the hook 29 is doubled and turns downward, as indicated at 30, and it is then turned upward, as indicated at 31; thus giving the hook approximately the shape of an "S" in horizontal position.

Adjacent each end of the plate are curved ribs 32 struck therefrom so as to project outward from the same face as the bearing 40 28; and between the bearing and the ribs 32 may be openings 33 to allow the metal to expand when the stamping is performed. Each of the ribs presents to the bearing a shoulder 34, which may be made slightly 45 concave; so that when the hook is turned to lie flat against the plate the upturned end 31 of the hook 29 will fit tightly against the shoulder 34 of one or the other of the ribs 32 and be held stationary. For this purpose 50 the end 31 must be bent so that the shank of the hook in the bearing 28 will be held firmly at that end while the extremity 31 will abut tightly against the shoulder 34 at the other. With such a construction the 55 hook can be laid flat against the plate 27 and the bearing 28 and rib 32 will project far enough from the plate 27 to prevent the inner face of the front 1 from rubbing against the hook, and gradually being worn 60 through by friction or torn by catching the extremity 31. In other words, the hook can always be held flat against the plate by the shoulder 34 when it engages this shoulder, and when the bag is out of service and 65 flattened, the hook cannot swing outward

away from the plate 27 so as to be forced through the front 1; and all danger of the hook 29 punching a hole in the bag is thus eliminated. Further, by the union of the two plates 23 and 27 by means of the barbs 70 26 the weight of the garment is supported entirely by hooks 4 and 29 and all stress is taken off the material of which the bag is made, the bag thus serving merely as an envelope in which a garment can be sealed when it is not wanted. The hook can easily be pushed away from either rib 32 with one's fingers, or with a knife blade or similar implement.

75 The clips 15 are preferably constructed as shown in Figure 18 by making them concave or dished, as at 35, on top; so that the edges can be taken hold of by the fingers and the swinging of the clips on the rivets 16 made easy. These clips are preferably of sheet metal, punched to provide projections 36 on their lower faces and thus make these lower faces somewhat rough, so that when they engage the folded over sections 6 and 7, there will be sufficient friction to hold them in the position required to keep the side of the bag closed up and make the turning of these clips difficult. Thus the opening of the bag accidentally when carelessly handled is rendered unlikely. To cooperate with the clips are washers 37 punched to provide similar projections 38, these washers to be located inside the bag and perforated in the middle to receive the rivet 16. A reinforcement 39 may be glued to the inside of the face front 1, and the rivet 16 may be tight enough to hold the washer 37 with projections 38 firmly in contact with this reinforcement 39. Hence, the clips 15 will always require some degree of force to move them from the position shown in Figure 3 to that shown in Figure 1 when the bag is to be opened.

80 In Figures 4 to 9 inclusive, another form of bag is illustrated which is made so that it can be opened along one side only; and which can be folded into the shape of a box before it is closed up, or allowed to remain relatively flat and be closed by turning over the edges of the open side, as the owner may prefer. This bag is likewise composed of a front 1 and back 2 and can be made by taking a piece of suitable material, such as strong paper, and folding it in the middle to make the permanently closed side; the same as in the case of the bag above described. To close it at the top and bottom, the back 2 may be provided with projections or flaps 3 to be folded over and glued to the upper and lower edges of the front 1; and this bag may have an inside pleat formed by longitudinal sections 17 as in the case of the bag shown in Figures 1, 2 and 3. Along the edges of the open side will be creases or score lines 5, as before, making sections

70

115

120

125

130

or portions 6 and 7; but in this instance the extremities of the portions 6 and 7 of the front will be attached to the extremities of the same portions or sections at the back; 5 because the flaps 3 will extend from the closed side across the top and bottom to the extreme edge of the opposite side. In addition to the score lines 5 there will be a longitudinal score line 40 extending down 10 the front face 1 and also down the back face 2; marking off, between the lines 40 in the front and back and the portions 6, somewhat wider portions 41 on the front and rear of the bag. Also across the front 1 and 15 back 2, near both the top and bottom of the bag, will be creases 42 extending from the closed side across to the extreme edge of the opposite side; and marking off transverse portions or sections 43 of the same 20 width as sections 41.

When this bag is to be closed without giving it the shape of a box, the sections 7 of the front and back will be folded over upon the front section 6, and then the sections 6 25 and 7 are further folded along the inner line 5 against the front 1 and secured by clips 15, the same as in the case of the bag of Figure 3. The outer edges of the sections 7 of both front and back can be reinforced if desired, and the bag can thus be laid flat, and opened and closed without expanding or distending it any further than the gusset at the permanently closed side will permit. As indicated at the upper and 30 lower right hand corners of Figure 5, the upper and lower ends of the sections 17 are in such position that they can be glued to the front 1 and back 2 near the top and bottom, if required.

0 The purpose of the additional creases 40 and 42 marking off the longitudinal portions or sections 41 and transverse portions or sections 43 is to enable the bag to be given a box form when the box form is wanted. 45 Merely to enable the bag to be handled for opening and closing while keeping it flat or collapsed nothing more than the creases 5 to mark off the sections 6 and 7 are needed; as the additional creases 40 and 42 are not 50 called into play when the bag is kept flat and closed by merely folding over the sections 6 and 7.

In addition to the creases 40 and 42, to 55 permit the bag to assume a box-shape I provide an additional score line or crease 44 in the front and back at the top and bottom of the portions or sections 41. These score lines 44 are diagonal and run from the creases 40 and 42 to the top and bottom of 60 the bag, at the adjacent corner of the sections 6; thus marking off at the top and bottom triangular sections 45 and 46. I also provide score lines 47 at the ends of the sections 17, these sections extending 65 diagonally from the extremities of the score

lines 42 at the closed side of the bag to the top and bottom at the inside corners of the sections 17; thereby marking off at the top of both sections triangular portions or sections 48 and 49. Of course it is understood 70 that the creases 42 will not only cross the front and back but cross the tops and bottoms of the sections 17 also; so that the creases 42 extend entirely around the circumference of the bag the same as the creases 75 5 and crease 40.

To give the bag its box-form, the front 1 and rear 2 must be bent along the upper and lower creases 42; so as to cause the sections 43 to come into line with each other and 80 occupy the same plane, as indicated in Figure 4. Hence, the sections 17 must also be brought into line and occupy the same plane and form a flat side face. As the front 1 and back 2 are moved away from each other, 85 and the sections 43 at the top turn downward and the sections 43 at the bottom turn upward so as to be horizontal, the tops and bottoms of the sections 17 bend along the creases 42, and as the parts pass from the 90 position shown in Figure 5 to Figure 6, the portions or sections 48 at the top and bottom turn about the lines 47 until they come into contact with the sections 49; and when the top and bottom of the bag are flat and 95 each presents a horizontal surface instead of an edge, the portions 49 will lie flat against the inside faces of the sections 43, and the portions 48 will be flat against the portions 49, as indicated in Figures 8 and 9. The bag 100 will then have a form of a box but will be open along one side. To close it along this side the portions 46 at the top must be turned downward and the same portions 46 at the bottom must be turned upward. As 105 these portions move, the creases 44 become well defined edges; as indicated in Figure 9, and as the sections 46 become vertical and lie in vertical planes, the sections 45 also become vertical, being folded around lines 44 110 to be against the sections 46. As a result, the portions 6 and 7 of the front 1 between the upper and lower score lines 42 can be brought into contact with the portions 6 and 7 at the back; and both the ends of the sections 6 and 7 on both front and back will be doubled over and inward; the upper ends being doubled over downward and the lower ends being doubled over upward; as indicated in Figure 9. The sections 6 and 7 can 115 then be folded over the same as in the case of the bag shown in Figure 3; and held fast by clips 15. The bag will then have the form of a complete box and can be suspended in that form by means of the hook 4, 120 which will be attached to the back 2 and be associated with a plate 27 inside; the same as in the case of the box shown in Figures 12 and 3.

At the top and bottom of the box shown 125

in Figures 4 to 9 inclusive I can use a reinforced strip 50 which will extend from the score line 40 across the inside of the bag to the opposite side; and its end adjacent the 5 sections 17 may be notched to receive the points of the sections 48; as indicated in Figures 8 and 9.

This type of bag enables the user to secure a slightly better appearance or effect by 10 giving it a box-form, than by merely closing it without giving it the box-form, simply by turning over the sections 6 and 7.

Having described my invention, what I believe to be new and desire to secure and 15 protect by Letters Patent of the United States is:—

1. A moth-proof and dust-proof bag open along one side to give access to the interior, said bag being foldable along said side to 20 seal the bag, the bag being capable of being sealed flat, and having creases to enable it to assume the shape of a box and be closed in that shape.

2. A hook for the inside of a bag, and a 25 plate upon which said hook is pivotally mounted, the plate being secured to the bag and having ribs provided with shoulders on each side of the hook to engage the end of the hook and retain it flat against the 30 plate.

3. A moth-proof and dust-proof bag closed along the bottom and one side and open along the top and opposite side to give access to the interior, the bag being 35 foldable along the top to be sealed thereat, strips having barbs secured to the bag adjacent the top, clips pivoted to said strips

to hold the bag closed at the top, the bag also being foldable along said opposite side to be sealed thereat, clips having projections to maintain the bag sealed along said opposite side, a hook inside the bag, a plate secured to the bag for pivotally supporting the hook, and ribs having shoulders on the plate to engage the hook and hold it flat 40 against the plate for the purpose set forth.

4. A moth-proof and dust-proof bag having a reinforcing strip therein at one end, said strip being secured to the front and rear of the bag, the bag being foldable 50 along one side to be sealed thereat, clips having roughened faces to maintain the bag sealed at said side, a plate inside the bag, a hook pivoted to the plate, and ribs having shoulders on the plate to hold the 55 hook against the plate as set forth.

5. A moth-proof and dust-proof bag open at one side to give access to the interior, and foldable along said side to seal same, the bag having a gusset at the opposite side, and being foldable along said first-named side to be sealed thereat, clips having roughened surfaces to maintain the bag sealed, the bag also having creases to enable it to assume the shape of a box and be 60 closed in that shape, a plate in the bag, a hook pivoted to the plate, and ribs on the plate having shoulders to engage the hook and hold it against the plate, as set forth.

In testimony whereof, I have signed my 70 name to this specification this 25th day of August, 1922.

GEORGE ROTTMAN.
